STOPPING MEANS FOR LOOMS

Carl D. Brown, Hopedale, Mass., assignor to
 Draper Corporation, Hopedale, Mass., a corporation of Maine

Application October 28, 1944, Serial No. 560,805

4 Claims. (Cl. 139—377)

The present invention relates generally to stop motions for automatic filling replenishing looms and, as illustrated herein, relates more particularly to stop motions for such looms which are conditioned for operation to stop the loom through the usual warp stop motion upon filling failure.

It is usual practice to provide means for stopping the loom when there is a filling failure due, for example, to filling breakage. Detection of such failure takes place in many instances at the filling replenishing side of the loom and stopping of the loom is usually accomplished through a filling fork feeler mechanism which operates through connections to the other side of the loom to move the shipper handle out of holding position and into stopping position to disengage the clutch and thus stop the loom. Such connections, however, are objectionable because of the number of parts and the consequent lost motion.

One object of the present invention is to provide stopping means for a loom by the use of which the filling fork slide will operate substantially directly to condition the parts to stop the loom. To this end and in accordance with one feature of the invention, the filling fork slide is provided with means for moving a stopping member into stopping position. As illustrated, the filling fork slide is provided with a cam surface arranged to bear against a spring pressed plunger on one end of a Bowden wire having its other end arranged below a knock-off finger of the usual mechanical warp stop motion and which will move said knock-off finger into position when the filling fork slide is moved upon the occurrence of filling failure. Thus, a simple and effective means is provided for stopping the loom within a minimum number of mechanical connections.

With the above and other objects and features in view, the invention will now be described with particular reference to the accompanying drawings in which:

Fig. 1 is a perspective view of the right hand side of a loom in which the present invention is embodied;

Fig. 2 is a similar view of the left hand side of the loom showing the knock-off mechanism; and

Fig. 3 is a detail view, partly in section, of the knock-off mechanism.

The entire loom is not shown in the drawings since the parts not shown are of usual construction. The construction and operation of the warp stop motion to which the present invention is applied is clearly described and claimed in United States Letters Patent No. 1,538,625 issued

May 19, 1925, in the names of H. A. Davis and Arthur S. Johnson to which reference may be had for a description of those parts thereof which are not shown or described herein.

5 The drawings show a filling fork 10 of usual construction which is arranged to be engaged by the filling to prevent operative connection between the fork 10 and the usual filling feeler slide 12, thereby preventing forward movement of the 10 filling slide and actuation of connections to the usual shipper handle of the loom.

The filling fork 10 is pivotally supported in the rear end portion of the filling feeler slide 12. The fork 10 is arranged to be tilted by engagement with the filling after the shuttle is picked into the right hand shuttle box 14 on the lay and thus raise the wire loop 16 so that it will not engage a hook 18 pivoted to the upper end portion of a filling motion lever 20. The filling motion lever 20 is pivoted at 22 to the loom frame and at its rear end engages or rests on a cam member 24. The filling motion lever 20 and the cam member 24 are of usual construction and operate to reciprocate the hook 18 during alternate picks of 15 the shuttle or, in other words, when the shuttle is in the right hand shuttle box 14. If the filling is broken, the tines of the filling fork 10 will meet no resistance as the tines pass between the bars of the grate 26 on the forwardly moving lay. As 20 a result, the loop 16 will engage the hook 18 and, when the filling motion lever 20 is rocked by the cam member 24, the filling feeler slide 12 will be moved forwardly to operate the loom stopping mechanism.

25 The forward end of the filling feeler slide 12 is provided with an inclined surface 28 which is arranged to engage and move a plunger 30 secured to one end of a Bowden wire fixed to the breast beam 32 of the loom by a supporting clip 34. The wire is enclosed in a flexible conduit 36 and extends along the breast beam 32 to the left hand side of the loom where it is secured to the side frame 38 by a tubular member 40. The wire enclosed in the flexible conduit 36 then extends 30 rearwardly to knock-off mechanism 42.

35 The knock-off mechanism is substantially the same as that disclosed in the above-mentioned patent to Davis et al., and includes a bracket 44 fixed in any suitable manner to the left hand side 40 frame 38 of the loom. The bracket 44 is provided with an upwardly extending portion 46 having an opening therein for receiving a bushing 48 in which a plunger 50 is arranged to reciprocate. The plunger 50 is hollow and is arranged to receive the Bowden wire in the conduit 36 from 45

the front of the machine and also the Bowden wire in a conduit 52 leading from the usual mechanical warp stop mechanism at the rear of the loom. The bracket 44 is provided with an upwardly extending projection 54 which enters the slot formed in the knock rod end 56 and serves to guide the rod end 56 and the rod 58 as it is oscillated during knock off and in starting the loom.

The knock off rod end 56 has pivotally mounted in the slot therein a knock off 60 pivoted in the rear end portion of rod end 56 and normally urged downwardly by a compression spring 62. When the plunger 58 moves upwardly, the knock-off 60 is swung upwardly and its forked end is moved into the path of movement of a bunter 64 fixed to the under side of the lay 15. Thus, when the lay 15 moves rearwardly toward back center, the bunter 64 will engage the knock-off 60 and move the knock-off rod 58 rearwardly. The forward end of the knock-off rod 58 is provided with a coupling 66 having a slot for receiving a pin or stud 68 fixed to the shipper handle 70. Thus, rearward movement of the knock-off rod 58 will cause the shipper handle 70 to be moved from its forward running position to its rear "stop" position. During this rearward movement of the shipper handle 70, the usual clutch mechanism of the loom will be released and the usual brake mechanism energized to stop the loom.

The construction and operation of the various elements has been described in detail, but it may be well for a clearer understanding of the invention to review briefly the operation of the device. When the shuttle has been picked out of the left hand box and has been properly boxed in the right hand shuttle box 14, the lay will continue its forward movement and the tines of the filling fork 10 will engage the filling between the shuttle and the selvage of the cloth being woven. The fork 10 will tilt and thus the loop 16 will not engage the hook 18. On the other hand, if there has been filling failure, the tines of the fork 10 will pass between the bars of the grate 26 and when the filling feeler lever is rocked clockwise by the cam 24, the hook 18 will engage the loop 16 and pull the filling feeler slide 12 forwardly. The cam surface on the forward end of the slide will force the plunger 30 toward the left, as viewed in Fig. 1. The plunger 30 will raise the knock-off 60 into the path of movement of the bunter 64 and the loom will be stopped as described above. It is evident that the above construction operates effectively and without appreciable lost motion to stop the loom.

Having thus described my invention, what I claim as new and desire to secure by Letters Patent of the United States is:

1. In a loom, means operated upon warp failure to stop the loom, a filling fork arranged to be tilted upon engagement with the filling, a slide on which the fork is pivoted, a loop on said fork, means having a projection thereon arranged to be engaged by said loop upon filling failure and for reciprocating said slide, a cam surface on said slide, and means interposed between said cam surface and said stopping means and arranged to actuate said stopping means during movement of said slide.

2. In a loom, an oscillating lay, warp stop mechanism including a member fixed to the lay and means movable into the path of movement of said member upon warp failure for stopping the loom, a filling feeler fork arranged to engage filling upon forward movement of the lay and to be tilted thereby, a slide having a cam surface thereon, means for reciprocating said slide upon failure of the fork to tilt because of filling failure, and a connection between the slide and said warp stop mechanism arranged to be moved into stopping position during forward movement of the slide.

3. In a loom, an oscillating lay, means operated upon warp failure to stop the loom, a filling fork arranged to be tilted upon engagement with the filling during forward movement of said lay, a slide on which the fork is pivoted, a loop on said fork, means having a projection thereon arranged to be engaged by said loop upon filling failure and reciprocating said slide, a cam surface on said slide, a spring-urged plunger arranged to be engaged by said cam surface when the slide moves forwardly, and a connection between said plunger and said stopping means to actuate said plunger and said stopping means to actuate said stopping means during forward movement of said slide.

4. In a loom, a reciprocating lay, means operated upon warp failure to stop the loom, a filling feeler fork arranged to be tilted upon engagement with the filling, a slide on which the fork is pivoted, cam operated means for reciprocating the slide upon filling failure, a loop on said fork arranged to engage said reciprocating means upon filling failure, a cam surface on said slide, a plunger engaging said cam surface and being arranged to be moved when the slide moves forwardly, a wire member connected to said plunger and being arranged to transmit movement of said plunger to said loom stopping means to condition said means for stopping the loom.

CARL D. BROWN.
